UNITED STATES PATENT OFFICE.

HAROLD E. McCREERY, OF APOLLO, PENNSYLVANIA, ASSIGNEE, BY DIRECT AND MESNE ASSIGNMENTS, TO APOLLO HOLDING CORPORATION, OF APOLLO, PENNSYLVANIA, A CORPORATION OF DELAWARE.

METHOD OF AND APPARATUS FOR OPENING SHEET PACKS.

Application filed November 8, 1924. Serial No. 748,777.

This invention relates to a method of and apparatus for opening sheet packs and more particularly to a method and apparatus adapted for separating the individual sheets of a pack of metal sheets which adhere during the process of manufacture.

In the manufacture of relatively thin metal sheets the stock employed is in the form of what are usually known as "sheet bars". These sheet bars, in thickness, run upward of one fourth inch and usually are eight inches wide, though sometimes the stock employed is as wide as fifteen inches. The sheet bars usually are rolled in thirty foot lengths after which they are cut in desired lengths depending on the width of the sheet to be rolled. After being so cut, the sections of the bar are placed in what is known as a "pair furnace" and heated, after which they are successively passed through hot rolls to reduce them in thickness. Two of the pieces are then placed together and again successively passed through hot rolls and further reduced in thickness, after which a number of the sheets are placed together and introduced into what is known as a "sheet furnace", where they are again heated. It is in the sheet furnace that the packs are made and each pack contains from two to sixteen or more sheets according to the gage of the sheets, the packs of lighter gage metal containing the larger number of sheets. After a pack is so formed and heated in the sheet furnace it is rolled as a unit between hot rolls where the sheets are brought out to the length required. The pack is then sheared to proper dimensions whereupon it is ready to be opened to separate the sheets.

It has been found that when sheet packs are so prepared a serious problem is presented in separating the sheets, the separation being accomplished only through rigorous manual labor and at considerable expense. It is the usual practice to grasp a corner of a pack in a large pair of tongs and vigorously shake the pack in rapid vertical movements to loosen the sheets at the corners of the pack after which each individual sheet is grasped at its loosened corner by the tongs and pulled upwardly to release the sheet. Where the operation is performed on packs of relatively large sheets it is necessary to repeat the operation

at the opposite corner of the pack and it is often extremely difficult to loosen a sheet from the pack due to the fact that heating the pack in the sheet furnace causes adjacent sheets to weld in spots and it requires great force to separate them.

It is an important object of the present invention to provide means for opening a corner of a pack and subsequently separating the individual sheets simultaneously without the expenditure of manual force.

A further object of the invention is to provide novel means for drawing the sheets through separating means in the form of slightly spaced relatively small parallel bars provided with means for absorbing any shocks transmitted thereto when the rollers are forced to separate tightly adhering sheets.

A further object of the invention is to provide means for gripping the corners of the sheets after they have been inserted between the separating rods, and to provide means for moving the gripping means to completely draw the sheets through the separating means after which the gripping means ceases to function as such and the sheets are released to permit their withdrawal by an operator.

A still further object of the invention is to provide novel means for reciprocating the gripping means whereby the latter is caused to move toward and away from the separating means to grasp the sheets and move them longitudinally to draw them through the separating means.

A further object of the invention is to provide means associated with the separating rods for preventing shearing stresses adjacent the ends of the rods when tightly adhering sheets are drawn between these rods.

Other objects and advantages of the invention will be apparent during the course of the following description.

In the drawings I have shown several assemblies of apparatus elements adapted for use in the practice of the method. In this showing,

Figure 1 is a plan view of the assembled apparatus.

Figure 2 is a fragmentary perspective view of a portion of a sheet pack showing the corners of the sheet initially separated,

Figure 3 is a side elevation of the machine,

Figure 18 is an enlarged fragmentary side elevation of the corner opening device shown in Figure 11, parts being shown in section,

35 Figure 19 is a section taken on line 19—19 of Figure 9,

Figure 20 is a detail sectional view on line 20—20 of Figure 9,

40 Figure 21 is a detail perspective view of one of the gripping members, and,

Figure 22 is a fragmentary side elevation of a portion of the chain.

Referring to the drawings the numeral 10 designates as a whole one sheet pack corner opening device employed in practicing the initial step of the method to be described.

This device comprises a generally rectangular base 11 provided adjacent one of its sides with a supporting roller 12, as shown in Figure 14. Forwardly of the roller 12, a T-shaped supporting member 13 is arranged and secured to the base 11 as at 14. The numeral 15 designates a pair of opening rollers arranged substantially at right angles

55 to each other as shown in Figure 14. These rollers preferably are formed of laminated metal as shown at 16 (see Figure 16). The laminations 16 are secured together in any suitable manner and are preferably arranged parallel to the axes of the rollers. As shown

60 in Figures 14 and 15 each of the rollers 15 is preferably conical in shape and is provided with an axial shaft 17 by means of

65 which it may be revolved in a manner to be described. As shown in Figure 16 the lami-

nations forming the rollers 15 preferably are staggered at their edges for a purpose to be described. The adjacent ends of the rollers 15 are journaled in bearings 18 secured to the base 11.

The remote ends of the rollers 15 are journaled in bearings 19 similarly secured to the base and provided with off-set ends 20 which are adapted to overhang the edges of a sheet pack when arranged in proper position by means of which the corners may be opened in a manner to be de-

scribed. Each of the rollers 15 is adapted to be driven through the medium of a sprocket chain 21 suitably connected with an electric motor 22.

In Figure 14 of the drawings I have shown a sheet pack 23 ar-

ranged in operative position in the corner opening device, the adjacent edges 24 and 25 of the pack being arranged in contact with the sides of the rollers 15.

As indicated by the arrows in Figure 14, the rollers 15 are adapted to rotate in opposite directions whereby the staggered edges of the laminations of the rollers will contact with the edges of the sheet pack, one roller tending to

move the adjacent edges of the pack downwardly while the other roller tends to move its adjacent edge of the sheet pack upwardly.

The operation of the corner opening de-

vice is adapted to separate one corner of the pack as indicated at 26 (see Figure 2). The roller 12 serves to permit the operator to readily slide the pack into position in contact with the rollers with its adjacent edges arranged beneath the offset portions 20 of the bearings 19.

The T-shaped member 13 supports the pack against downward movement while the offset ends 20 prevent upward movement of the pack.

Referring to Figures 1, 3 and 4, the nu-

meral 27 designates as a whole the sheet opening device. This device employs a sub-

stantially horizontal base 28 having prefer-

ably integrally cast arms 29 upstanding therefrom.

An extension 30 is connected with the base and projects forwardly of the

machine a substantial distance to provide a working platform and also to provide an ex-

tension on the base whereby the latter may be effectively secured to the floor of the

building in which the apparatus is em-

ployed. The upstanding arms 29 are ar-

ranged inwardly of the outer ends of the base 28 and are connected therewith by webs 31

as shown in Figures 1 and 4, to provide

pockets 32. Each of the upstanding arms 29 is provided with an elongated arcuate slot

33 as shown in Figures 5 and 6. The outer

face of each of the upstanding arms is

curved on an arc of a circle as shown at 34,

each of these curved faces forming a por-

tion of a vertical cylinder.

A plurality of arcuately arranged hori-

zontal parallel spaced rods 35 are arranged

between the upstanding arms 29 and project

through the slots 33 a substantial distance beyond the upstanding arms. These rods are preferably formed of untempered chrome nickel steel and in actual practice these rods are preferably approximately three-fourths of an inch in diameter. The rods 35 are preferably formed of the material stated in order that they may possess great toughness and ability to withstand shocks without fracturing. As shown in Figure 6, the rods 35 are preferably slightly smaller in diameter than the width of the slots 33 and the rods are surrounded intermediate the upstanding arms 29 with collars 36 preferably formed of hardened steel and somewhat larger than the slots 33. The collars 36 are closely arranged in end to end relation but fit fairly loosely with respect to each other so that each of the rods is permitted to bend slightly without creating any binding action between the contacting ends of the collars 36.

As shown in Figures 5 and 6, an oscillating plate 37 is arranged outwardly of each of the upstanding arms 29 and is provided with a convex inner face curved similarly to the adjacent outer face of the upstanding arm 29. It will be apparent from Figure 6 that the plates 37 are adapted to partake of limited oscillating movement in contact with the faces 34 and each is provided with a slot similar to and arranged in alignment with the slots 33, to receive the rods 35. Anchoring plates 39 are arranged outwardly of the plates 37 in spaced relation thereto as clearly shown. The plates 39 are apertured as at 40 for the reception of the ends of the rods 35 as shown in Figure 5. The ends of the rods are anchored to the plates 39 in any suitable manner as by providing nuts 41 threaded on the ends of the rods and contacting with the outer faces of the plates 39. As shown in Figures 5 and 6, rows of relatively heavy springs 42 are arranged between the inner faces of the plates 37 and 39. These springs are intended to exert great outward force against the plates 39 so as to tension the rods 35 as will be obvious. With the device above described assembled as shown, the space between each adjacent set of collars 36 is preferably substantially equal to the thickness of the thickest sheet intended to be inserted therebetween as will become obvious.

Referring to Figures 1 and 3, the numeral 43 designates a plurality of preferably U-shaped supports alined rearwardly of the sheet opening means at right angles to the separating rods. Each of these supports includes upstanding arms 44 as clearly shown in Figure 8. H-beams 45 are arranged over the ends of the arms 44 as shown in Figures 3 and 8 to serve as trackways in a manner to be described, and are secured to the arms 44 by bolts 46.

Referring to Figures 3 and 8, the numeral 47 designates a pair of U-beams secured against the inner faces of the upstanding arms 44 below the tops thereof, for a purpose to be described. Stub shafts 48 are secured to two of the outer U-shaped supporting members 43 and extend inwardly from each arm thereof as shown in Figure 8. Each of the stub shafts is provided inwardly of its adjacent arm 44 with a sprocket 49 and a chain 50 passes over each pair of sprockets as shown in Figures 3 and 8. The shafts 48 which carry the outer sprockets 49 extend outwardly through their adjacent arms 44 and are provided at their outer ends with gears 51 which mesh with gears 52 carried on a transverse shaft 53. One end of the shaft 53 extends outwardly beyond the gear 52 and is provided with another gear 54 adapted to be driven by a pinion 55 carried on the shaft of a motor 56. A clutch 57 is arranged on the shaft 53 between the gears 52 and 54 in order that rotation of the gears 51 and 52 and consequent operation of the chains 50 may be stopped or started at will. The clutch is of any standard construction employing a spring (not shown) for normally maintaining the clutch in operation. As shown in Figure 1, a lever 58 is pivotally connected intermediate its ends as at 59, one end of the lever being operatively connected with the shiftable member of the clutch 57 as shown. A pulley 60 is pivotally mounted adjacent the opposite end of the lever 58. A cable 61 is arranged substantially parallel to the beams 45 and has its outer end passed about the pulley 60 and secured to the free end of the lever 58. The opposite end of the cable is connected as at 62 with one end of a bell-crank lever 63. A link 64 is pivotally connected at one end as at 65 with the opposite end of the bell-crank lever 63 and at its opposite end with a depending crank 66 carried by a shaft 67. The shaft 67 extends transversely of the upstanding arm 29 and is journaled in bearings 68 carried thereby. The opposite end of the shaft is provided with an operating handle 69. A similar shaft 67 is arranged across the opposite upstanding arm 29 and is similarly journaled in bearings 68. This shaft 67 is also provided with a depending arm 66 to which is pivotally connected a link 70. The link 70 is bent intermediate its ends as at 71 to pass around the forward U-shaped supporting member 43. The opposite end of the link 70 is also pivotally connected with the bell-crank lever 63. It will be obvious that rotation of either shaft 67 by its handle 69 will swing the depending arms 66, thus oscillating the bell-crank lever 63 and operating the cable 61 to swing the lever 58 above its pivot to engage or disengage the clutch 57.

Referring to Figures 8 and 9, the numeral 72 designates a sheet pack leaf gripping device as a whole. As shown this device comprises a carriage 73 provided with transverse shafts 74 at the outer ends of which are mounted wheels 75. As clearly shown in Figure 8, the wheels 75 are adapted to travel within one side of each of the beams 45, resting on the lower bases thereof. The carriage 73 is provided with a central depending member 76 having a vertical slot 77 cut transversely therethrough. Complementary guide bearings 78 are adapted to reciprocate within the slot 77. As shown in Figure 20, the guide bearings 78 are provided with rectangular portions 79 extending into the slot 77 with their ends abutting. Flanges 80 engage the outer faces of the depending member 76 and collar portions 81 extend outwardly from these flanges. Set screws 82 are threaded in the collar portions 81 and are adapted to grip a transverse shaft 83 passing through openings 84 in the guide bearings 78. The outer ends of the shaft 83 are provided with wheels 85 as clearly shown in Figures 8 and 20. In the position shown in Figure 8 of the drawings, the wheels 85 are adapted to run on angle iron tracks 86 arranged below the U-beams 47.

As shown one link of each of the chains 50 is provided with an eye 87 adapted to engage the shaft 83 whereby the carriage 73 will be caused to travel as the chain is moved. The chains are adapted to travel in the direction indicated by the arrow in Figure 3 of the drawings and it will be apparent that when the eyes 87 reach the forward sprocket 49 they will move upwardly around this sprocket carrying with them the shaft 83 causing the latter to move upwardly in the slot 77. This position will be maintained until the eyes reach the rear ends of the runs of the chains 50 whereupon the hooks will move downwardly carrying the shaft 83 back to the position shown in Figures 8 and 9 of the drawings.

As shown in Figures 8, 9 and 19, the carriage 73 is provided with a vertical transverse upstanding wall 88 connected with the carriage by side webs 89. A plate 90 is secured against the wall 88 by screws 91 as clearly shown in Figure 19. A plurality of gripping members 92 are arranged adjacent the plate 90. Each of the members 92 is provided with a rearwardly extending arm 93 adjacent each side and the arms of each gripping member are provided with aligned bearing openings 94 through which extend pivot pins 95. Each of the arms 93 is further provided at its inner end with vertically extending flanges 96. As shown in Figure 9 the adjacent flanges 96 are adapted to engage each other to limit the pivoting movement of the members 92. The flanges 96 are not intended, however, to entirely fill the

spaces between the members 92 so that the latter are adapted to partake of limited swinging movement about their pivot pins 95. The outer ends of the members 92 are provided with enlarged heads 97 having parallel adjacent faces and the ends 98 of the members 92 are arranged on an arc as shown in Figure 9 to correspond with the curved arrangement of the rods 35 as clearly shown in Figure 3.

A head 99 is pivotally connected as at 100 with the upper end of the plate 90. The lower face of the outer end of the head 99 is arranged adjacent the upper face of the upper gripping member 92 as shown. The rear end of the head 99 is provided adjacent each side with a stub shaft 101 and these shafts are pivotally connected with the upper ends of links 102. The carriage 73 is provided at its forward end with ears 103 in which is mounted a shaft 104. A clamping head 105 has its rear end 106 arranged between the ears 103 and surrounding the shaft 104 whereby the head is adapted to partake of vertical swinging movement. The lower ends of the links 102 are pivotally connected with stub shafts 107 projecting outwardly from each side of the forward portion of the clamping head 105. The upper face of the forward portion of the clamping head 105 is arranged adjacent the lower face of the lowermost gripping member 92.

Supporting plates 108 are riveted or otherwise secured as at 109 with the depending member 76 as shown in Figures 8 and 9. Each supporting plate is provided with an outwardly extending horizontal stub shaft 110 to which is pivotally connected one end of a lever 111. The opposite end of the lever is provided with a slot 112 which receives the shaft 83. Collars 113 are connected with the shaft 83 outwardly of the levers 111 to properly maintain the latter in position. A link 114 is arranged adjacent each of the levers 111. As shown each of the links 114 is pivotally connected as at 115 with one of the arms 111 while the upper ends of the links 114 are provided with slots 116 receiving the stub shafts 107 between the links 102 and the clamping head 105. A spring 117 surrounds the link 114 intermediate its ends. The lower end of the spring 117 is supported on a collar 118 which rests on a transverse pin 119 passing through the link 114. The upper end of the spring bears against a collar 120 which in turn contacts with a shoulder 121 formed on the link 114 below the slot 116.

In Figures 10 to 12 inclusive and 17 and 18, I show an alternative form of sheet pack corner opening device. The numeral 122 designates supporting members on which are mounted a pair of tracks 123 preferably in the form of H beams as shown. A car-

riage designated as a whole by the reference numeral 124 is arranged between the tracks 123. The carriage 124 comprises upper and lower sections 125 and 126 respectively. 5 The lower portion 126 is provided adjacent each end with wheels 127 adapted to be supported on the tracks 123. As shown in Fig. 1 the tracks 123 are arranged transversely of the machine and it will be obvious that 10 the carriage is adapted to be moved by means of its wheel mounting, toward and away from the center of the machine. As shown, a sprocket chain 128 is arranged between and parallel to the tracks 123. This 15 sprocket chain is adapted to be actuated through a sprocket carried on a shaft 129 provided outwardly of the tracks with a gear 130. A motor 131 is provided with a shaft 132 carrying a pinion 133 meshing with the gear 130. Current to the motor is 20 adapted to be controlled through a manually controlled switch 134 arranged at any convenient point. It will be obvious that when the switch 134 is closed the chain 128 will 25 be operated. As shown in Figure 11, one link of the chain 128 is provided with a hook 135 adapted to engage a transverse shaft 136 mounted to vertically reciprocate in slots 137 formed in depending members 138 carried by the lower section 126. It will be 30 obvious that the hook 135 will operate to move the carriage 124 toward and away from the center of the machine when the chain 128 is actuated.

35 The upper and lower sections 125 and 126 are pivotally connected through links 139. As shown in Figure 11, the links are pivotally connected at their upper ends with the section 125 through pins 140 and at their 40 lower ends with the section 126 through pins 141. A spring 142 is arranged between the sections 125 and 126 and is adapted to normally project the section 125 upwardly. The section 125 is provided at its opposite 45 end with ears 143 to which links 144 are pivotally connected at their upper ends. An operating lever 145 is pivotally connected between the lower ends of the links 144 as at 146. The outer end of the lever 145 is 50 provided with a handle 147 while the inner end is provided with a cam face 148 as shown in Figure 18. The cam face 148 is 55 adapted to engage the lower cam face 149 of a lug 150 carried by the outer end of the section 126. It will be obvious that 60 when the parts are in the position shown in dotted lines in Figure 18, the cam face 148 may be engaged beneath the cam face 149 and depression of the handle 147 will swing 65 the parts to the solid line position forcing the section 125 downwardly to a position parallel to the section 126 for a purpose to be described. As clearly shown in Figure 70 75 17 the upper section 125 is provided with a flat lower face 151 connected to a beveled

face 152. The section 126 is provided with an upper face a portion of which is flat as at 75 153 and arranged parallel to the face 151. The section 126 is also provided with an inclined face 154 similar to the face 152 and a downwardly inclined face 155. The sheets 80 of a sheet pack 23 may be arranged between the sections 125 and 126 when the latter are in the dotted line position shown in Figure 18 and when the handle 147 is depressed the angularity of the faces 152 and 154 causes the corners 26 of the sheets to be separated as shown in Figure 17.

In general the operation of the device is 85 carried out by initially separating the sheets adjacent one corner of the pack by either of the two devices previously described as being adapted for that purpose. The opened corner of the pack is then fed toward the separating bars with each sheet of the pack 90 inserted between adjacent bars of the separating means. I provide convenient means for assisting in feeding the pack toward the separating means. As shown in Figures 1, 10 and 13, I provide a pair of trackways 156 95 preferably in the form of H-beams as shown in Figure 13. These trackways are preferably inclined upwardly as shown in Figure 10, and a carriage 157 is arranged to move longitudinally between the trackways. The 100 carriage is mounted on wheels 158 adapted to roll on the inner portions of the bases of the H-beams 156 as will be clearly understood. The carriage embodies an electro-magnet indicated diagrammatically at 159 105 in Figure 13. Means are provided for supplying current to the electro-magnet when desired. As shown in Figure 13, the wheels 158 are mounted on shaft sections 160 which are insulated from each other and the lead wires 161 and 162 of the electro-magnet are grounded on the shaft sections 160, as shown. One of the trackways 156 is provided with a conducting strip 163 suitably 110 insulated from the trackways as at 164. The conducting strip 163 extends from the lower end of the trackways to a point spaced from the upper end and the insulation 164 is raised beyond the end of the conducting strip as shown at 165, so that its upper 115 face is flush with the upper face of the conducting strip. A wire 166 is connected between the conducting strip 163 and a suitable source of current 167, the opposite pole of the source of current being connected through a wire 168 with the opposite H-beam 156 from whence the current passes 120 into the opposite lead wire of the electro-magnet through the adjacent wheel 158. A manually controlled switch 169 is preferably arranged in the wire 168 to disconnect the electro-magnet from the source of current whenever desired. It will be obvious 125 that with the switch 169 closed, current will be supplied to the electro-magnet as long as 130

the wheels at one side of the carriage 157 are in contact with the conducting strip 163. The carriage 157 is moved manually along the trackways 156 and when the wheels thereof pass beyond the upper end of the conducting strip 163 the circuit to the electro-magnet obviously will be broken.

A lever 170 is arranged on each side of the carriage 157 as shown. These levers are 10 pivotally connected on the forward shaft sections 160 and are connected at their forward ends by a cross bar 171 as shown in Figures 1 and 13. The opposite ends of the levers also are connected by a cross bar 172 15 while the levers are connected intermediate their ends to springs 173, the opposite ends of the springs being suitably connected to the carriage to move the lower ends of the levers upwardly and the forward ends of 20 the levers and the cross bar 171 downwardly. When the carriage 157 is in its lowermost position as shown in Figure 10 of the drawings the cross bar 172 is adapted to contact with an abutment 174 which is adapted to 25 swing the lower ends of the levers 170 forwardly and downwardly to lift the bar 171 for a purpose to be described. A block 175 is arranged across the lower ends of the trackways 156 and a bumper 176 is arranged 30 forwardly of this block and connected therewith by compression springs 177 to reduce the shock occasioned when the carriage 157 is released from a position adjacent the upper end of its movement and permitted to 35 move downwardly by gravity.

Means are provided for facilitating the removal of the separated sheets of a sheet pack after passing through the separating members 36. As shown in Figure 1, a plurality of bearings 178 are mounted adjacent one of the H-beams 45 and rollers 179 are arranged between these bearings. The upper portions of the rollers 179 are preferably substantially flush with the upper faces 45 of the beams 45 whereby the separated sheets are permitted to roll from the tops of the beams in the manner to be described.

The operation of the apparatus is as follows:

50 In carrying out the first step of the method of separating the sheets, I propose to initially separate the portions of sheets adjacent one corner of a pack in such a manner that the extreme corners are separated a substantial distance to adapt them for insertion between the sleeves or collars 36. The sleeves being relatively small, however, it will be obvious that the separation of the corner of the pack need not be great. For 55 separating a corner of a pack, I have found either of the alternative constructions illustrated for that purpose to be efficient in operation. When the form of corner opening device illustrated in Figures 14 to 16 inclusive is employed, the pack is inserted as

clearly shown in Figure 14, the roller 12 being adapted to support the pack to permit its easy insertion with the edges in contact with the members 15 and arranged beneath the offset arms 20. The motors 22 70 are then started and the corner of the pack separated as previously described and as shown in Figure 2 of the drawings. When the device shown in Figures 11, 12, 17 and 18 is employed the handle 147 is raised to 75 permit the spring 142 to lift the upper section 125 a sufficient distance to permit the insertion of a corner of the pack. The handle 147 is then operated to clamp the upper section 125 downwardly as previously 80 described whereupon the relative arrangements of the faces 151 to 154 inclusive (see Figure 17) serve to bend the corners of the sheets as shown, with the extreme corners separated. When either of the corner opening devices described is employed, the corners will be separated substantially as shown in Figure 10 with the extreme corners of the separated portion arranged a distance apart substantially equal to the distance between the spaces of the sleeves 36 to permit their ready insertion therebetween.

I provide the carriage 157 to facilitate the operation of the separating means, particularly when the form of corner opening device shown in Figures 11, 12, 17 and 18 is employed. The pack to be opened is laid diagonally with its rear corner resting on the carriage 157 and its forward corner resting on the nearer track 123. The switch 169 100 is then closed, energizing the magnet 159 and effectually holding the pack in position on the carriage. After the head 125 is lifted, the carriage 157 is manually advanced to cause insertion of the corner of the pack between the heads 125 and 126 whereupon the corner opening operation is carried out. The head 125 is then released by moving the handle 147 upwardly whereupon the switch 134 is closed causing the chain 128 to move the carriage 124 to the outer ends of the tracks 123 by virtue of the engagement between the hook 135 and the shaft 136. It will be obvious that when the hook passes over the sprockets at opposite ends of the chain 128 the direction of movement of the carriage 124 will be reversed automatically and it is merely necessary when moving the carriage in either direction to close the switch 134 a sufficient length of time as will 110 be obvious.

The second step in the method comprises drawing the sheets through the separating sleeves 36 while the latter remain relatively stationary to effectually separate the portions of the sheets which most tightly adhere. After the corner opening operation has been completed the carriage 157 is moved manually to bring the separated corners of the pack in proximity to the sleeves or col- 120 125 130

lars 36 whereupon the corners of the sheets are introduced between adjacent pairs of the sets of sleeves 36 and the carriage 157 is moved a sufficient distance to permit the separated corners of the sheets to project through the opposite sides of the sleeves 36. The motor 56 is then placed in operation and with the clutch controlling transmission of power to the drive gears in engagement, it will be obvious that the sprockets 49 will be rotated to drive the chains 50. The eyes 87 connected to the chains 50 obviously will move therewith, the direction of travel thereof depending on whether they are in the upper runs of the chains or the lower runs. Assuming the eyes to be in the lower runs of the chains, it will be obvious that they will travel toward the forward end of the machine, the chains moving in the direction of the arrow shown in Figure 1. Since the shaft 83 extends through the eyes 87 of each chain, it will be obvious that the carriage 73 will be moved toward the sleeves 36. When the eyes reach the extreme forward ends of the chains, that is in horizontal alignment with the forward shaft 48 the faces 98 of the gripping member 92 will be arranged in close proximity to the sets of sleeves 36 to receive the projecting corners of the sheet pack therebetween. When the parts of the carriage 72 are in the position shown in Figures 8 and 9, with the shaft 83 near the lower end of the slot 77 the links 114 will be moved downwardly thus lowering the forward end of the head 105 and, through the links 102, lifting the forward end of the head 99. As the eyes 87 approach the upper run of the chain by passing around the forward sprockets 49 the shaft 83 will be carried upwardly moving with it the levers 111 and links 114. This action lifts the forward end of the head 105 and lowers the forward end of the head 99 by virtue of transmitted upward movement of the links 102. By the time the shaft 83 reaches the upper limit of its movement as indicated by the dotted lines in Figure 9, the projecting corners of the sheets will be tightly gripped between the gripping members 92. Since the sheets vary in thickness, I provide means for permitting effective gripping of sheets of varying thickness. The links 114 are provided with the slots 116 to permit the links to move upwardly a short distance until the collars 121 contact with the lower faces of the heads 105. Thus it will be seen that the springs 117 effect a cushioned upward movement of the head 105, the compression of the springs 117 varying according to the thickness of the sheets being separated. Continued movement of the chains 50 obviously will move the shaft 83 toward the rear end of the device carrying with it the carriage 73. The eyes 87 being arranged on the upper runs of the chains 50, it will be obvious that the parts of the carriage 73 will be retained in the position just described with the sheets clamped between the members 92. It will be obvious that rearward movement of the carriage 73 will draw the sheets of the pack rearwardly forcing the sleeves 36 between the sheets and effectually separating them. I provide the sleeves 36 of hardened steel and relatively short to permit them to alter their positions from time to time to present new wearing surfaces to the metal of the sheets being drawn therebetween. When the carriage 73 reaches the rear of the upper runs of the chains 50, the eyes 87 will pass over the rear sprockets 49 carrying with them the shaft 83. As the shaft 83 passes downwardly around the rear sprockets 49 it will be obvious that the levers 111 will be carried back to the solid line position shown in Figure 9, releasing the gripping action of the members 92. I prefer to make the tracks 45 and chains 50 of a sufficient length to permit the longest sheets to be drawn through the sleeves 36 before the carriage reaches the extreme rear end of its movement. As the sheets are released from the gripping members 92, it will be obvious that they will lie across the tops of the tracks 45 whereupon they may be gripped by the operator and moved transversely of the tracks to remove them, the rollers 179 assisting in the removal of the sheets. As previously stated, the rods 35 are formed of metal possessing great toughness and ability to withstand sudden shocks. This is due to the fact that the rollers 36 must encounter sudden shocks at points where the sheets of a pack are tightly adhered and it is necessary that these sudden shocks be withstood without causing damage to the machine. In order to insure the rods 35 against breakage due to shearing stresses, I provide the mountings shown and described for the outer ends of the rods. The springs 42 are preferably very heavy and accordingly are adapted to exert a tremendous outward force against the plates 39 tending to prevent bending of the rods 35. However, any tendency of the rods to bend will be taken up by the mounting of the members 37 against the upright arms 29. The curvature of the contacting faces of these members permits them to move slightly relatively when the rods 35 bend and it will be obvious that the plates 39 will turn with the rods so that they retain their right angular relation thereto. The stiffness of the rods and the tension of the springs are such, however, as to reduce any bending tendency of the rods to a minimum and any bending action that takes place is relatively slight.

After the carriage has completed its rearward movement the eyes 87 will pass around

the rear sprockets 49 as previously described and will move forwardly again carrying with them the carriage 73. After the gripping members 92 have moved the initially separated corners of the sheets until the pack has passed almost completely through the separating means, the switch 169 may be opened to deenergize the magnet 159 and the carriage 157 may be moved 10 downwardly and forwardly to the position shown in Figure 10 to be in readiness to receive a new pack to be opened. After the end of one pack has passed through the separating means a new pack is placed in 15 position so that the operation of separating the corners of the pack may be completed by the time the carriage again reaches its forward position.

Thus it will be seen that the method practiced by the apparatus just described comprises two steps, namely, separating by suitable means a corner of a sheet pack and inserting the separated corners through separating means from one side thereof and 25 drawing the separated corners away from the separating means from the opposite side thereof. I have found that the method may be very quickly and efficiently carried out and the sheets wholly separated without 30 causing any damage thereto which would render them useless for the commercial uses for which they are intended.

As previously stated, the number of sheets in a pack varies according to the gage of 35 the sheets, some of the heavier gage sheets being formed in packs containing only two sheets while many of the lighter gage sheets are packed sixteen or more in a pack. I prefer to employ a sufficient number of the rods 35 to care for packs containing the 40 largest number of sheets commercially packed and the spaces between the slots 36 preferably are sufficient to admit the heaviest gage sheets which are pressed into packs. 45 The arrangement of the slots in the members 33 and 37 permits the rods 35 to flex toward each other slightly when the thinner sheets are run through the slots 36 as will be obvious but the flexing of the rods when the 50 lighter sheets are run through will be too slight to cause any damage to the rods.

It is to be understood that the method and assemblages of apparatus elements above described are to be taken as preferred 55 examples of the same, and that various changes in the shape, size and arrangement of parts may be resorted to without departing from the spirit of the invention or the scope of the subjoined claims.

Having described my invention, I claim:

1. Apparatus of the character described comprising a separating member adapted to be received between a pair of sheets introduced from one side thereof, and means 65 adapted to simultaneously grasp and hold

portions of the sheets at the opposite side of said separating member, said separating member and said means being bodily movable with respect to each other to increase the distance therebetween.

2. Apparatus of the character described comprising a separating member adapted to be received between a pair of sheets introduced from one side thereof, means adapted to engage and hold portions of the sheets at the opposite side of said separating member, and means for bodily moving said separating member and said engaging means with respect to each other substantially in a single common plane to increase the distance therebetween.

3. Apparatus of the character described comprising a plurality of separating members adapted to receive therebetween portions of pack sheets inserted from one side thereof, gripping means adapted to simultaneously grasp portions of all of the sheets at the opposite side of said separating members, and means for moving said separating members and said gripping means with respect to each other to increase the distance therebetween.

4. Apparatus of the character described comprising a plurality of separating members adapted to receive therebetween portions of pack sheets inserted from one side thereof, and means for drawing said inserted portions of the sheets from the opposite side of said separating means, said means including a member adapted to be received between the inserted portions of each adjacent pair of sheets.

5. Apparatus of the character described comprising a separating member adapted to be received between portions of pack sheets inserted from one side thereof, means movable substantially in a single common plane with said separating member for drawing said inserted portion of the sheet from the opposite side of said separating means, and means for releasing said drawing means when said separating member has passed completely through the sheets.

6. Apparatus of the character described comprising a plurality of separating members adapted to receive therebetween portions of pack sheets inserted from one side thereof, and means for gripping the inserted portions of the sheets from the opposite side of and moving them completely through said separating members, said gripping means including a member adapted to be received between the inserted portions of each adjacent pair of sheets.

7. Apparatus of the character described comprising a separating member adapted to be received between portions of pack sheets inserted from one side thereof, means for simultaneously gripping the inserted portions of all of the sheets from the oppo-

- site side of and drawing them away from said separating member, and means for releasing said gripping means when said separating member has passed completely 5 through the sheets.
8. Apparatus of the character described comprising a plurality of spaced parallel bars adapted to receive therebetween portions of pack sheets inserted from one side thereof, means for simultaneously gripping the inserted portions of all of the sheets from the opposite side of said bars, and means for moving said gripping means away from said bars.
13. Apparatus of the character described 65 comprising a plurality of spaced parallel bars adapted to receive therebetween portions of pack sheets inserted from one side thereof, a carriage arranged on the opposite side of said bars, means for supporting said carriage for reciprocation toward and away from said bars, means carried by said carriage for gripping the inserted portions of the sheets when said carriage is moved away from said bars, and means for releasing said gripping means after said carriage has moved a predetermined distance away from said bars.
- 10 14. Apparatus of the character described comprising a plurality of spaced parallel arcuately arranged bars corresponding in arrangement to the separated portions of sheets of one corner of a pack and adapted to receive therebetween said separated portions of the pack inserted from one side of said bars, and means on the opposite side of said bars for gripping the inserted portions of the sheets and drawing them away from said bars.
- 15 15. Apparatus of the character described comprising a plurality of spaced parallel bars corresponding in arrangement to the separated portions of sheets of one corner of a pack and adapted to receive therebetween said separated portions of the pack inserted from one side of the bars, movable means on the opposite side of said bars for drawing the inserted portions of the sheets away from said bars, and means for releasing the sheets from said drawing means when the latter has moved a predetermined distance away from said bars.
- 20 16. Apparatus of the character described comprising a plurality of spaced parallel bars adapted to receive therebetween portions of the sheets of a pack inserted from one side thereof, means for drawing said inserted portions of the sheets from the opposite side of said bars, and means opposing the bending of said bars.
- 25 17. A device constructed in accordance with claim 16 wherein said bars are surrounded by a plurality of relatively short sleeves arranged in end to end relation, the sleeves of each bar being spaced from those of each adjacent bar.
- 30 18. Apparatus of the character described comprising a plurality of spaced parallel bars, means for supporting the ends of said bars, sleeves surrounding each of said bars, the sleeves of each bar being spaced from those of each adjacent bar and adapted to receive therebetween separated portions of the sheets of a pack inserted from one side, and means arranged on the opposite side of said bars for gripping the inserted portions of the sheets and drawing them through said sleeves.
- 35 40 45 50 55 60 65 70 75 80 85 90 95 100 105 110 115 120 125
10. Apparatus of the character described comprising a plurality of separating members adapted to receive therebetween portions of pack sheets inserted from one side thereof and a member arranged on the opposite side of said separating members and movable simultaneously in a single plane directly toward and away from said separating members, said movable member being provided with means operable during movement away from said separating members for gripping the inserted portions of the sheets.
11. Apparatus of the character described comprising a plurality of separating members adapted to receive therebetween portions of pack sheets inserted from one side thereof, and a member arranged on the opposite side of said separating members and movable toward and away from said separating members, said movable member being provided with automatic means operable during movement away from said separating members for gripping the inserted portions of the sheets and upon movement toward said separating members for releasing the sheets.
12. Apparatus of the character described comprising a plurality of spaced parallel bars adapted to receive therebetween portions of pack sheets inserted from one side thereof, a carriage arranged on the opposite side of said bars, means for supporting said carriage for reciprocation toward and away from said bars, and means carried by said carriage for gripping the inserted ends of the sheets when said carriage is moved away from said bars.

19. Apparatus of the character described comprising a pair of spaced upstanding arms provided with slots, a plurality of spaced parallel bars arranged between said arms with their ends projecting through said slots, plates secured to the projecting ends of said bars, resilient means connecting said plates and said arms, and means arranged to one side of said bars for gripping portions of the sheets of a pack inserted through said bars from the opposite side, said gripping means being movable away from said bars to draw the sheets completely therethrough. 65
20. A device constructed in accordance with claim 19 provided with means for releasing said sheets from said gripping means when the latter has moved a sufficient distance to draw the sheets completely through said bars. 70
21. Apparatus of the character described comprising a pair of upstanding arms provided with slots, a plurality of spaced parallel bars arranged between said arms with their ends projecting through said slots, a plurality of sleeves surrounding each of said bars, plates secured to the projecting ends of said bars, compression springs arranged between said plates and said arms, tracks arranged to one side of said bars and extending transversely therefrom, a carriage adapted to move on said tracks, and means mounted on said carriage for gripping portions of the sheets of a pack inserted through said sleeves from the opposite side, said carriage being movable on said tracks away from said sleeves until the sheets have been completely drawn through said sleeves. 75
22. A device constructed in accordance with claim 21 provided with a chain connected to said carriage to effect movement thereof toward and away from said sleeves, and means controlled by said chain for rendering said gripping means inoperative and operative as said carriage moves toward and away from said sleeves respectively. 80
23. A device for drawing metal sheets of a pack through separating means comprising a movable carriage, and gripping means carried thereby for engaging portions of the sheets inserted through the separating means, said gripping means including a gripping member adapted to be received between portions of each adjacent pair of sheets. 85
24. A device for drawing metal sheets of a pack through separating means comprising a movable carriage, a plurality of spaced pivoted fingers each adapted to be received between portions of adjacent pairs of sheets inserted through the separating means, and means for clamping said fingers in contact with the sheets. 90
25. A device constructed in accordance with claim 24 provided with drive means for moving said carriage, and means controlled by said drive means for operating said clamping means. 95
26. A device for drawing metal sheets of a pack through separating means comprising a pair of tracks, a continuous chain arranged parallel to said tracks, a carriage arranged on said tracks, connections between said chain and said carriage for reciprocating the latter along said tracks, and means associated with said carriage for gripping portions of sheets inserted through the separating means and drawing them therethrough as said carriage moves in one direction. 100
27. A device constructed in accordance with claim 26 provided with means controlled by said chain for rendering said gripping means operative throughout a portion of the travel of said chain. 105
28. A device constructed in accordance with claim 26 wherein said gripping means comprise a plurality of spaced fingers pivotally connected with said carriage, and each adapted to be arranged between portions of each adjacent pair of sheets. 110
29. A device for drawing metal sheets of a pack through separating means comprising a pair of tracks, a continuous chain arranged parallel to said tracks, a carriage arranged on said tracks, connections between said chain and said carriage for moving the latter along said tracks, a plurality of slightly spaced parallel gripping members pivotally connected with said carriage and adapted to be moved in proximity to the separating means to receive therebetween portions of sheets inserted through the separating means, heads pivotally connected to said carriage adjacent the uppermost and lowermost gripping members thereof, a link pivotally connected with said heads on opposite sides of the pivots thereof, and means for actuating one of said heads. 115
30. A device constructed in accordance with claim 29 provided with means controlled by movement of said chain for actuating one of said heads. 120
31. A device for drawing metal sheets of a pack through separating means comprising a pair of tracks, a pair of sprockets arranged parallel to said tracks, a continuous chain passing around said sprockets, a carriage arranged on said tracks, a member connected between said carriage and said chain, and means associated with said carriage for gripping portions of sheets inserted through the separating means and drawing them therethrough as the carriage moves in one direction. 125
32. A device for drawing metal sheets of a pack through separating means comprising a pair of tracks, a pair of aligned

sprockets arranged parallel to said tracks, a continuous chain passing around said sprockets, a carriage arranged on said tracks, said carriage being provided with a 5 slot, a shaft mounted in said slot and connected with said chain to be driven thereby, and means associated with said carriage for gripping portions of sheets inserted through the separating means and drawing them 10 therethrough as said carriage moves in one direction.

33. A device for drawing metal sheets of a pack through separating means comprising a pair of tracks, a pair of aligned sprockets arranged parallel to said tracks, a continuous chain passing about said sprockets, an eye carried by one link of said chain, a carriage arranged on said tracks, said carriage being provided with a vertical slot, 15 a shaft extending transversely through said slot and through said eye, and means associated with said carriage for gripping portions of sheets inserted through the separating means and drawing them therethrough 20 as said carriage moves in one direction.

34. A device for drawing metal sheets of a pack through separating means comprising a pair of tracks, a pair of vertical aligned sprockets arranged adjacent each track substantially parallel thereto, a chain passing around each pair of sprockets, each of said chains being provided with an eye carried by one link thereof, said eyes being transversely aligned, a carriage arranged on said 25 tracks and provided with a vertical slot, said slot being arranged in a portion of the carriage adapted to travel between said chains, a transverse shaft mounted in said eyes and extending through said slot, and means associated with said carriage for gripping portions of sheets inserted through the separating means and drawing them therethrough as said carriage moves in one direction.

35. A device constructed in accordance 45 with claim 34 provided with means connected between said shaft and said gripping means for actuating the latter when the carriage moves in one direction.

36. A device for drawing metal sheets of a pack through separating means comprising a pair of tracks, a pair of vertical aligned sprockets arranged between and parallel to said tracks, one link of said chain being provided with a transverse eye, a carriage arranged on said tracks, said carriage being provided with a depending portion arranged adjacent said chain and provided with a vertical slot, a transverse shaft arranged in said eye and said slot, a plurality of slightly spaced horizontal gripping members pivotally connected to said carriage and adapted to be moved in proximity to the separating means to receive therebetween portions of sheets inserted through the separating 50 means, and means connected between said

shaft and said gripping members for actuating the latter when the carriage moves away from the separating means.

37. A device for opening a corner of a sheet pack comprising a pair of rollers having roughened surfaces, the rollers being arranged with their axes substantially at right angles to each other, and adapted to receive therebetween a corner of a sheet pack in peripheral engagement therewith, and means for rotating said rollers.

38. A device constructed in accordance with claim 37 wherein said rollers are formed of a plurality of laminations having offset edges.

39. Apparatus of the character described comprising a plurality of spaced parallel bars adapted to receive therebetween portions of the sheets of a pack inserted from one side thereof, means for drawing said inserted portions of the sheets from the opposite side of said bars, and yielding means opposing the bending of said bars.

40. Apparatus of the character described comprising a pair of upstanding arms provided with slots, a plurality of spaced parallel bars arranged between said arms with their ends projecting through said slots, a plurality of sleeves surrounding each of said bars, plates secured to the projecting ends of said bars, compression springs arranged between said plates and said arms, tracks arranged to one side of said bars and extending transversely therefrom, a carriage mounted on said tracks, means mounted on said carriage for gripping portions of the sheets of a pack inserted between said sleeves from the opposite side, said carriage being movable on said tracks away from said sleeves until the sheets have been completely drawn through said sleeves, an endless chain connected to said carriage to effect movement thereof toward and away from said sleeves, and automatic means for rendering said gripping means inoperative and operative as said carriage moves toward and away from said sleeves respectively.

41. A device of the character described comprising a plurality of spaced separating members adapted to receive therebetween separated portions of a sheet pack inserted from one side thereof, a trackway arranged at the opposite side of said separating members, an endless chain arranged parallel to said trackway, a carriage movable on said trackway, connections between said chain and said carriage for moving the latter, a plurality of slightly spaced parallel gripping members pivotally connected with said carriage and adapted to be moved in proximity to the separating members to receive therebetween portions of sheets inserted through the separating members, means for limiting movement of said gripping members away from each other, heads pivotally

connected to said carriage adjacent the uppermost and lowermost gripping members, a link pivotally connected with said heads on opposite sides of the pivots thereof, and means for actuating one of said heads.

42. Apparatus of the character described comprising a separating member adapted to be received between edge portions of a pair of sheets introduced from one side thereof, means for engaging and holding the portions of the sheets at the opposite side of said member, means for moving said member and said engaging means away from each other, and means for releasing said engaging means from the sheets when said separating member is passed entirely therebetween.

43. Apparatus of the character described comprising a separating member adapted to be received between a pair of sheets introduced from one side thereof and means

adapted to engage and hold portions of the sheets at the opposite side of said separating member, said separating member and said means being bodily movable with respect to each other substantially in a single common plane to increase the distance therebetween. 25

44. Apparatus of the character described comprising a separating member adapted to be received between a pair of sheets introduced from one side thereof, and means 30 adapted to simultaneously engage and hold portions of the sheets at the opposite side of said separating member, said separating member and said means being bodily movable with respect to each other substantially 35 in a single common plane to increase the distance therebetween.

In testimony whereof I affix my signature.

HAROLD E. McCRARY.
